[57] CLAIM

The ornamental design for a fragrance container, as shown and described.

DESCRIPTION

FIG. 1 is a perspective view of a fragrance container showing my new design;

FIG. 2 is a front elevational view;

FIG. 3 is a rear elevational view;

FIG. 4 is a view looking from the left of FIG. 2;

FIG. 5 is a view looking from the right of FIG. 2;

FIG. 6 is a top plan view;

FIG. 7 is a bottom plan view; and

FIG. 8 is a perspective view showing a modified form of my new design.
